CONTROL MECHANISM FOR DISTRIBUTING BUCKETS

Application filed September 18, 1929. Serial No. 393,462.

This invention relates to distributing apparatus and more particularly to control mechanisms for distributing buckets.

In concrete mixing machines, considerable shock is produced on the distributing bucket as the mixed aggregates are dumped into the bucket from the mixing drum for distributing at the desired position along the boom or bucket support. Without some means for holding the bucket stationary on the boom during this receiving of the aggregates from the mixing drum, considerable material would be wasted because of the tendency of the bucket to move outwardly on the boom as the aggregates are poured therein. A downward inclination of the boom would also tend to cause the bucket to move outwardly along the boom away from the mixing drum, which is undesirable. Further, it is highly desirable to operate the bucket dumping mechanism at any point along the boom and particularly without a separate tripping control which would possibly necessitate an additional operator or at least would require additional time to be expended on the part of the operator at each dumped batch.

In the present day, the conservation of time and energy is extremely important to the road builder or other concrete user to enable work to be completed in the least time possible.

To this end we have provided a mechanism for retaining or locking the distributing bucket in position during the receiving of the aggregates from the mixing drum.

A further object of the invention is to provide a means for releasing the locking mechanism incident to motion of the bucket operating cable in a direction to cause the bucket to travel outwardly along the boom.

Another object of the invention is to provide a means for dumping the bucket incident to motion of the cable in a direction which tends to draw the bucket inwardly along the boom.

A still further object of the invention is to provide a means for restoring the bucket to a closed position during its travel adjacent the inward end of the boom.

We have also afforded a construction whereby a single means is used to actuate both the bucket latching or locking means and the bucket dump tripping mechanism.

A still further object of the invention is to provide a shiftable shuttle which is adapted to release the bucket locking means when shifted in one direction under the action of the bucket operating cable, and effecting dumping of the bucket when shifted in the opposite direction.

Other and further objects of the invention will become apparent as the description of the same proceeds, and the novel features thereof will be defined by the appended claims.

In the drawings, Fig. 1 is a fragmentary side elevation of a portion of the boom and bucket, the full lines showing the bucket in position for outward movement as indicated by the solid arrow, and the dumping mechanism being in closed position, the dotted lines showing the bucket on the inward movement as indicated by the dotted arrow and the dumping mechanism being in dumped position and beginning to engage the restoring means;

Fig. 2 is a vertical cross sectional view through the inner end of the boom looking towards the bucket, parts of the bucket and carriage being broken away for the sake of clearness;

Fig. 3 is an enlarged detailed view of the carriage showing the latch mechanism in latched position in full lines and in released position for outward movement to dumping position in dotted lines, parts being broken away and shown in section; and

Fig. 4 is a similar view as Fig. 3 showing the bucket in the course of inward movement near the inner end of the boom, the dumping mechanism being in partly restored position.

Like numerals refer to like parts in the several figures of the drawings in which 1 denotes the boom or support along which the carriage 2 is adapted to travel on the rollers 3, the carriage supporting the bucket 4 in the usual manner. Formed on the carriage is an extension 5 with which a shuttle 6 is adapted to cooperate. The shuttle is

formed with a longitudinal slot 7 which is slidably engaged by the guide pins 8 secured to the extension 5 in any suitable manner. The shuttle is preferably formed with an extension 9 to which the ends of the bucket operating cable 10 are secured as at 11.

Fixed to the boom 1, adjacent the inward end is a stop member 12 which is adapted to cooperate with a latch member having a stop engaging arm 13, a shuttle engaging arm 14 and a third arm 15 which is adapted to cooperate with a spring 16 or other device for normally holding the latch member in stop engaging position. Obviously any suitable means for producing this result might be employed. The stop member is so positioned along the boom as to cause the bucket to be held in the proper position with respect to the discharge chute from the mixing drum.

The shuttle 6 has formed on each end transverse flanges 17 and 18. An outhaul pull on able 10, assuming the bucket to be in latched position for receiving the mixed batch from the mixing drum, causes the flange 18 on the shuttle to engage the arm 14 of the latch member, thereby rotating the latch member about the pivot 19 to the position shown by the dotted lines in Fig. 3. Further movement of the cable causes the shuttle to shift on the guide pins until flange 18 engages the extension 5 of the carriage, whereupon motion is then transmitted to the carriage by the cable.

Journalized in the carriage in any suitable manner is the actuating shaft 20 for operating the bucket opening and closing member or door (not shown) in the usual manner, as for example by means of the bell cranks 21 fixed to the ends of the actuating shaft 20 and having pivoted thereon the links 22 for cooperating with the hanger rods 23 extending on each side of the bucket. Fixed to the actuating shaft is the door trip mechanism 24 having an extension 25 which is adapted to cooperate with the flange 18 on the shuttle. After the bucket has been drawn outwardly along the boom by the cable 10 to the desired position, an inward pull on the cable causes the shuttle to shift inwardly until the flange 18 strikes the extension 25, thereby causing dumping of the bucket. This dumping may be produced by either a direct reversal of the motion of the bucket operating cable or the parts may be so arranged as to cause dumping by the stopping of the motion of the cable and allowing the inertia of the bucket to trip the door.

In order to restore the dumping mechanism to position for receiving the next batch from the mixing drum, a pair of extensions 26 and 27 are formed on the tripping device 24 and are provided with rollers at the ends thereof. Fixed to the boom adjacent the inward end are the cam members 30 and 31 for cooperating with the rollers 28 and 29.

Assuming the parts being in dumped position as shown by the dotted lines in Fig. 1, roller 28 first engages cam 30 during the inward motion of the carriage, causing the tripping mechanism to rotate the actuating shaft 20 until the carriage has advanced sufficiently far to enable roller 29 to engage cam 31. Continued movement of the carriage after roller 29 has engaged 31 causes the door operating members to assume a position as shown by the full lines in Fig. 3, the bell cranks 21 and links 22 passing the dead center position with respect to the actuating shaft 20 and thereby producing a locking action. A means for adjusting the final position of the trip mechanism is afforded by the bolt 32 which may be adjusted with relation to a stop member 33 fixed to the carriage.

In Fig. 2, the shuttle is shown as having an extension 34 on the upper portion thereof, constituting a guard or cable guide. Also in Fig. 3 the carriage is shown as provided with the usual bumper device 35 for reducing the shock when the bucket reaches the innermost position along the boom.

The operation of the invention will be apparent from the foregoing description and may be briefly summarized as follows:

Starting with the bucket in position for receiving the aggregates from the mixing drum, an outward pull on the cable 10 shifts the shuttle to cause flange 18 to engage arm 14 of the latch member, thereby disengaging arm 13 from the stop member 12. Further pull on the cable produces a further shift of the shuttle until flange 18 engages the extension 5 on the carriage, whereupon motion is transmitted to the carriage for causing it to travel along the boom in an outward direction. Upon reaching the desired point along the boom at which the aggregates are to be dumped, the motion of the cable is reversed and an inward pull causes the shuttle to shift in a rearward direction until flange 18 engages the extension 25 on the trip member 24 which rotates the actuating shaft 20 until the dead center relation of the bucket actuating members is destroyed and the bucket door falls open, thereby dumping the aggregates. A further inward pull on the cable shifts the shuttle still further rearwardly until the flange 17 engages the extension 5 on the carriage, whereupon motion is now transmitted to draw the carriage inwardly along the boom.

As the carriage approaches the inward end of the boom, roller 28 engages cam 30 producing a partial closing of the bucket door. Further inward motion of the carriage causes roller 29 to engage cam 31 which produces a final closing and locking of the door. Cams 30 and 31 are in spaced relation to permit roller 29 to be rotated into position for engagement with cam 31. When the bucket reaches the position for receiving the

next batch of aggregates during its inward travel, the latch member 18 is caused to engage stop 12 under the action of the spring 16, thereby securing the bucket against any 5 movement during receiving of the aggregates from the mixing drum.

While the detail construction of the several parts has been shown and described, the invention is not confined thereto as changes and 10 alterations may be made without departing from the spirit of the invention as defined by the appended claims.

Having thus described our invention, what we claim as new and desire to secure by Letters Patent is:—

1. In a distributing machine, the combination of a support, a carriage adapted to travel along said support, a cable operable in reverse directions to impart corresponding movement to the carriage, a bucket supported by said carriage, said bucket having an opening and closing member, means for retaining said opening and closing member in closed position, means for preventing movement of the bucket in one direction, and means for releasing the same, said last named means constituting an actuating means for releasing the bucket opening and closing member.

2. In a distributing machine, the combination of a support, a carriage adapted to travel along said support, a cable operable in reverse directions to impart corresponding movement to the carriage, said bucket having an opening and closing member, means for retaining said opening and closing member in closed position, means supported by said carriage and engaging said support for preventing movement of the bucket in one direction, and a shiftable shuttle mounted on said carriage and connected to said cable whereby said shuttle may be shifted to permit movement of the bucket incident to movement of the cable in one direction and releasing said bucket opening and closing member incident to movement of the cable in the opposite direction.

3. In a distributing machine, the combination of a support, a carriage adapted to travel along said support, a cable operable in reverse directions to impart corresponding movement to the carriage, a bucket supported by said carriage, said bucket having an opening and closing member, trip means for retaining said opening and closing member in closed position, a stop member adjacent one end of said support, a latch member mounted on said carriage for engaging said stop member, and a shuttle on said carriage for releasing said latch member preliminary to movement of the bucket incident to movement of the cable in one direction, said shuttle being adapted to actuate said trip means incident to movement of the cable in the opposite direction.

4. In a distributing machine, the combination of a support, a carriage adapted to travel along said support, a cable operable in reverse directions to impart corresponding movement to the carriage, a bucket supported by said carriage, said bucket having an opening and closing member, trip means for retaining said opening and closing member in closed position, a stop member adjacent one end of said support, a latch member mounted on said carriage for engaging said stop member, a shuttle on said carriage for releasing said latch member preliminary to movement of the cable in one direction, said shuttle being adapted to actuate said trip means incident to movement of the cable in the opposite direction, and cam means associated with said trip means for restoring said opening and closing member to closing position. 70

5. In a distributing machine, the combination of a support, a carriage adapted to travel along said support, a cable operable in reverse directions to impart corresponding movement to the carriage, a bucket supported by said carriage, a stop member on said support, a latch member pivotally connected to said carriage and extending forwardly and upwardly for engaging said stop member, and a freely slidable member on said carriage 95 connected to the cable and cooperating with said latch member whereby to disengage said latch member incident to movement of the cable in one direction and preliminary to movement of the bucket. 100

6. In a distributing machine, the combination of a support, a carriage adapted to travel along said support, a cable operable in reverse directions to impart corresponding movement to the carriage, a bucket supported by said carriage, an opening and closing member for said bucket, means for retaining said opening and closing member in closed position, said means including an operating shaft, means on said carriage operable to release said opening and closing member incident to movement of the cable, and means for restoring said opening and closing member to closed position, said means including a trip member fixed to said operating shaft and having a plurality of arms extending therefrom, roller members rotatably carried by said arms, and a plurality of cam members on said support for cooperating with said roller members to effect rotation of said operating shaft. 115

7. In a distributing machine, the combination of a support, a carriage adapted to travel along said support, a cable operable in reverse 125 directions to impart corresponding movement to the carriage, a bucket supported by said carriage, an opening and closing member for said bucket, means for retaining said opening and closing member in closed posi- 130

tion, said means including an operating shaft, means on said carriage operable to release said opening and closing member incident to movement of the cable, and means for 5 restoring said opening and closing member to closed position, said means including a trip member fixed to said operating shaft and having a plurality of arms extending therefrom, roller members rotatably carried by 10 said arms, and a plurality of cam members on said support for successively cooperating with said roller members to effect rotation of said operating shaft.

8. In a distributing machine, the combination of a support, a carriage adapted to travel along said support, a cable operable in reverse directions to impart corresponding movement to the carriage, a bucket supported by said carriage, an opening and closing member for 15 said bucket, means for retaining said opening and closing member in closed position, said means including an operating shaft, means on said carriage operable to release said opening and closing member incident to movement 20 of the cable, and means for restoring said opening and closing member to closed position, said means including a trip member fixed to said operating shaft and having a plurality of arms extending therefrom, roller 25 members rotatably carried by said arms, a plurality of cam members on said support for cooperating with said roller members to effect rotation of said operating shaft, and means for limiting the rotation of the same.

30 9. In a distributing machine, the combination of a support, a carriage adapted to travel along said support, a cable operable in reverse directions to impart corresponding movement to the carriage, a bucket supported by said carriage, an opening and closing member for 35 said bucket, means for retaining said opening and closing member in closed position, said means including an operating shaft, means on said carriage operable to release said opening and closing member incident to movement of the cable, and means for restoring said opening and closing member to closed position, said means including a trip member fixed to 40 said operating shaft and having a plurality of arms extending therefrom, roller members rotatably carried by said arms, a plurality of cam members on said support for cooperating with said roller members to effect rotation of said operating shaft, and means for adjustably limiting the rotation of the same.

45 10. In a distributing machine, the combination of a support, a bucket adapted to travel along said support, a cable for actuating said bucket and shiftable with respect to said bucket, means for latching said bucket in position on the support, means for releasing said latching means incident to shifting of the cable with respect to the bucket in one 50 direction and means for dumping said bucket.

incident to shifting of the cable with respect to the bucket in the opposite direction.

55 In testimony whereof we affix our signatures.
